[57] CLAIM

The ornamental design for an electronic commerce terminal enclosure for a vending machine, as shown and described.

DESCRIPTION

FIG. 1 is a left side front perspective view of an electronic commerce terminal enclosure for a vending machine showing my new design;

FIG. 2 is a right side rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line showing on FIGS. 1, 3 and 5-8 is for illustrative purposes only and forms no part of the claimed design.
